UNITED STATES PATENT OFFICE.

HARRY E. KELLEY, OF NIAGARA FALLS, ASSIGNOR TO THE ONEIDA COMMUNITY, (LIMITED,) OF KENWOOD, NEW YORK.

SNAP-HOOK.

SPECIFICATION forming part of Letters Patent No. 430,857, dated June 24, 1890.

Application filed March 24, 1890. Serial No. 345,110. (No model.)

To all whom it may concern:

Be it known that I, HARRY E. KELLEY, of Niagara Falls, in the county of Niagara, in the State of New York, have invented new and useful Improvements in Snap-Hooks, of which the following, taken in connection with the accompanying drawings, is a full, clear, and exact description.

This invention relates to the class of snap-hooks in which the hook and its shank, which together I term the "body," are formed of sheet metal and corrugated transversely to stiffen the same.

The present invention consists in an improved construction of a tubular sheet-metal snap-hook body designed more particularly for use on a hitching strap or rein of a harness and for analogous purposes.

The invention is fully illustrated in the annexed drawings, in which—

Figure 1 is a side view of a snap-hook embodying my improvements. Fig. 2 is a face view of the same. Fig. 3 is an enlarged transverse section on line $x-x$, Fig. 1; and Fig. 4 is a longitudinal section on line $y-y$, Fig. 2.

Similar letters of reference indicate corresponding parts.

a and a' represent two strips of sheet metal, which are corrugated or formed concavo-convex in cross-section throughout the main portion of their lengths, and preferably with laterally-projecting flanges $c c$ along the edges of said main portions. The end portions of said strips are flattened or laterally straight, and one end portion of each is bent longitudinally into the shape of the hook h , while the other end portions are comparatively straight to form the integral attaching-shank

d of the snap-hook. Said strips are disposed with their concave sides facing each other and with the flanges $c c$ and end portions of the two strips in contact with each other, and are rigidly united at their ends by rivets $r r$ and r' passing through the two strips $a a'$. The rivets $r r$, which pass through the broad end portions of the metal strips, I also utilize for securing to the shank d the snap or spring plate s , which bears with its free end against the inner side of the free end of the hook h in the usual manner. The broad end

of the shank d , I provide with a laterally-elongated loop l for the attachment of the snap-hook to a strap. This loop I preferably form of a wire bent into the requisite shape, 55 and I secure the same to the shank d of the snap-hook by forming the broad end portions of the metal strips $a a'$ with transverse grooves $e e$ in their adjacent sides and passing one of the long portions of the loop l through said 60 grooves. To further insure the rigid connection of the loop to the shank d , I curve the central portions of the grooves $e e$ from the end of the shank, as shown at e' , and bend the loop accordingly, so as to allow it to lie 65 in the grooves throughout the length thereof, the loop being inserted before the metal strips $a a'$ are united, and an additional rivet i inserted in the two metal strips between the curved central portion of the aforesaid grooves 70 and end of the shank d .

Having described my invention, what I claim as new, and desire to secure by Letters Patent, is—

1. The improved tubular snap-hook composed of two separate strips of sheet metal corrugated in cross-section throughout the main portions of their lengths and terminating with transversely straight end portions, said strips being disposed with their concave 80 sides facing each other, and united by rivets through the flat end portions and bent longitudinally into the hook shape at one end and terminated with an integral straight and transversely-flat shank at the opposite end, 85 and a spring-plate rigidly secured to said shank and bearing with its free end on the inner side of the end of the hook, all constructed and combined substantially as described and shown. 90

2. As an improved article of manufacture, a snap-hook body composed of two strips of sheet metal rigidly united and formed with transverse grooves in the adjacent sides of the shank, a wire loop passing through said grooves, and a rivet passing through the said metal strips between the inclosed wire loop and end of the snap-hook shank, and the snap attached to said shank, as set forth. 95

3. The within-described snap-hook body, 100 composed of two strips of sheet metal corrugated in cross-section throughout the main

portions of their lengths and terminated with transversely straight end portions, said strips being rigidly united with their concave sides facing each other and having the adjacent 5 sides of the end portions of the shank formed with transverse grooves curved at their centers from the end of the shank, a wire link passing through the said grooves, and a rivet 10 passing through the metal strips between the curved central portions of the aforesaid

grooves and end of the shank, and the snap attached to said shank, substantially as described and shown.

In testimony whereof I have hereunto signed my name this 14th day of March, 1890. 15

HARRY E. KELLEY. [L. S.]
